DESIGN FOR A DISPLAY STAND FOR PACKAGED MERCHANDISE

Ernst Borregard, Woodmere, N. Y.

Application September 12, 1939, Serial No. 87,157

Term of patent 3½ years

To all whom it may concern:

Be it known that I, Ernst Borregard, a citizen of the United States of America and residing at Woodmere, Nassau County, State of New York, have invented a new, original, and ornamental Design for a Display Stand for Packaged Merchandise, of which the following is a specification, reference being had to the accompanying drawing, forming part thereof.

In the drawing,
Figure 2 is a side elevation of the display stand for packaged merchandise, showing my design.
I claim:

The ornamental design for a display stand for packaged merchandise, as shown.

ERNST BORREGARD.
